UNITED STATES PATENT OFFICE.

HEINRICH SCHNATH, OF BIELEFELD, GERMANY, ASSIGNOR TO THE FIRM KUXMANN & CO., KOMM.-AKT.-GES., OF BIELEFELD, GERMANY.

MACHINE FOR SPREADING ARTIFICIAL MANURE.

Application filed June 12, 1926, Serial No. 115,611, and in Germany July 10, 1924.

This invention relates to an improvement in machines for spreading artificial manure, of the kind comprising a storage container for the reception of the manure to be spread and having at its bottom a controllable outlet slot into which project the distributing finger of an endless chain and its object is to arrange instead of said chain a laterally adjustable mechanically driven endless ribbon having integral means thereon for a finer distribution and spreading of much smaller quantities of manure through said outlet slot than is possible with the use of endless chains.

The accompanying drawing illustrates the improvement: Fig. 1 is a cross-section through the storage container with the endless ribbon at its bottom, Figs. 2 and 3 show plan views of part of said ribbon in two different constructional forms thereof, Fig. 4 is a similar view to Fig. 1, showing a modified arrangement of the endless ribbon, and Fig. 5 shows a plan view of part of said latter ribbon.

Referring to Figs. 1, 2 and 3:—The storage container *a* is, in a way known in the art, arranged between and carried by the guide-wheels of the machine, this being not illustrated as it is the conventional art. The endless ribbon *b*, preferably of steel, is so arranged in the longitudinal direction and at the bottom of said container that its lower part lies beyond the container while its upper part is located within the latter upon the bottom *c* of the same with one edge thereof projecting laterally from within the container through the outlet slot *d* at the bottom of the container, said slot being controlled by an outer slide *m* in a way known in the art. The endless ribbon is mechanically driven from one of the guide-wheels of the machine in any appropriate manner not illustrated. The endless ribbon *b* is either formed like a sawblade at

its edge *e* projecting through the outlet slot *d* (Fig. 2), or provided on its whole length with parallel obliquely directed transverse slots *f* (Fig. 3), whereby the action of the endless ribbon is considerably increased.

As shown in Figs. 4 and 5, the endless ribbon *b* can also be located laterally beyond the container *a* and fitted on its whole length at one edge with fingerlike oblique projections *g* which at the upper part of the ribbon pass through the storage container above the bottom thereof and project laterally from within the container through the outlet slot *d*, the ribbon running over guiding-rollers *h*. In this case, the ribbon can also run, instead of horizontally, in vertical or in any other direction. To avoid a slipping of the ribbon, it can be provided at one or both of its edges with notches *i* engaging over pins *k* on the guiding-rollers *h*. The ribbon *b* can be laterally shifted by means of a known lever control *n*, in order to let the fingers *g* project more or less deeply through the outlet slot *d*.

Instead of the horizontal position of the ribbon *b*, or of the fingers *g* respectively, illustrated, parallel to the bottom *c* of the container, the ribbon, or the said fingers respectively, can also run at any appropriate angle of inclination thereto.

What I claim, is:—

In a machine for spreading manure, the combination with a storage container having an outlet slot at its bottom, of a mechanically driven endless steel ribbon, integral distributing fingers thereon projecting into said container through its outlet slot, and a lever control in connection with said ribbon for laterally shifting the latter and thereby adjusting said fingers to a more or less deep engagement in said outlet slot.

In testimony whereof I have hereunto set my hand.

HEINRICH SCHNATH.
